(57) **CLAIM**

The ornamental design for jewelry with gradient gemstone pattern, as shown and described.

DESCRIPTION

FIG. 1 is a top perspective view of jewelry with gradient gemstone pattern showing my new design;

FIG. 2 is a top plan view of the jewelry with gradient gemstone pattern shown in FIG. 1;

FIG. 3 is a bottom plan view of the jewelry with gradient gemstone pattern shown in FIG. 1

FIG. 4 is a left-side elevational view of the jewelry with gradient gemstone pattern shown in FIG. 1;

FIG. 5 is a right-side elevational view of the jewelry with gradient gemstone pattern shown in FIG. 1;

FIG. 6 is a rear elevational view of the jewelry with gradient gemstone pattern shown in FIG. 1;

FIG. 7 is a front elevational view of the jewelry with gradient gemstone pattern shown in FIG. 1; and,

FIG. 8 is an enlarged top plan view of a portion of the jewelry with gradient gemstone pattern shown in FIG. 2.

The broken lines shown in the drawings represent portions of the jewelry with gradient gemstone pattern that form no part of the claimed design. The gradient stippling from one
